DESIGN FOR A RADIO CABINET

Robert L. Weyhing, Detroit, and Percival D. Swibold, Highland Park, Mich., assignors to Weyhing Bros. Mfg. Co., Detroit, Mich., a corporation of Michigan

Application December 5, 1939, Serial No. 88,704

Term of patent 7 years

To all whom it may concern:

Be it known that we, Robert L. Weyhing and Percival D. Swibold, citizens of the United States, residing at Detroit, in the county of Wayne and State of Michigan, and Highland Park, in the county of Wayne and State of Michigan, respectively, have invented a new, original, and ornamental Design for a Radio Cabinet, of which the following is a specification, reference being had therein to the accompanying drawing, forming part thereof.

Figure 1 is a plan view of a radio cabinet, showing our new design;

Fig. 2 is a front elevational view thereof.

Fig. 3 is an end elevational view;

Fig. 4 is a perspective view of the closed cabinet; and

Fig. 5 is a similar view to Fig. 4, with the interior of the cabinet exposed.

We claim:

The ornamental design for a radio cabinet, as shown.

ROBERT L. WEYHING.
PERCIVAL D. SWIBOLD.
